William Edwards. Letter Patent Oct 14th 1812.

The subject referred to in these Letters Patent, and making part of the same, containing a description in the words of the said William Edwards himself of his Machine for Compressing Leather.

This Machine is of Brass, Copper, Iron or a composition of both, also the roller may be of various sizes, the most useful one is six inches long and three inches in diameter, made perfectly round and true with quoins at the ends, these are inserted into sockets secured to the end of a piece of timber of a width corresponding to the length of the roller, the opposite end of the timber which should be about nine feet long is connected by iron pivots to a piece of timber of six inches square of considerable length so placed that it will be elastic or will spring - placed in a horizontal position which will bring the timber to which this roller is fixed in a perpendicular position; the roller is made to vibrate by being connected with a horizontal wheel with a crank and the rollers by the principle of levers is brought with force upon the leather which should be placed on a bed of solid timber the size of which should be adapted to the proportion of a circle made by the vibration of the roller, sole leather treated with this machine requires little or no hammering by the shoemaker and from its being fully extended is used by the shoemakers with a rowing of at least ten per centum and is more solid and durable.
